Primary Examiner — Ricky Pham

CLAIM

We claim the ornamental design for a chair, as shown and described.

DESCRIPTION

FIG. 1 is a front perspective view of a chair, according to an embodiment;

FIG. 2 is a front view of a chair of FIG. 1;

FIG. 3 is a rear view of a chair of FIG. 1;

FIG. 4 is a right side view of a chair of FIG. 1, the left side view is a mirror image of the right side view of FIG. 4;

FIG. 5 is a top view of a chair of FIG. 1; and,

FIG. 6 is a bottom view of a chair of FIG. 1.

The dashed lines are for purposes of illustrating environmental structure and form no part of the claimed design.

1 Claim, 6 Drawing Sheets
